UNITED STATES PATENT OFFICE.

DAVID CARL, OF NEW YORK, N. Y., ASSIGNOR OF ONE-HALF TO NORMAN P. S. SCHLOSS,
OF MOUNT VERNON, NEW YORK.

COMBINATION PLUG AND SOCKET.

Application filed January 6, 1922. Serial No. 527,379.

To all whom it may concern:

Be it known that I, DAVID CARL, a citizen of the United States, and resident of New York city, in the county of New York and State of New York, have invented certain new and useful Improvements in Combination Plugs and Sockets, of which the following is a specification.

This invention relates to an electrical fixture and more particularly to a combination electrical plug and socket, and has special reference to the provision of a unitary plug and socket especially adapted for connecting standard base receptacles with standard plugs to render the former serviceable for use with various electrical household articles.

Electrical household articles such as the electric iron, electric heater, toaster, percolator, etc., are manufactured and sold with the provision of a male plug and a detachable combination plug, with the latter constructed to be insertible in and received by the standard lamp socket or receptacle. Although these household articles may therefore be used with and attached to the standard lamp socket, the plug or combination plug forming part of these household articles is not adapted and cannot be received by the base type of receptacle which is commonly met with and widely employed in residence installations. For the purpose of increasing the usefulness of the household articles and for adapting the same to be used with both types of receptacles occurring in residence installations, I have found it desirable to provide a novel combination of plug and socket especially adapted to be received by and fit into the standard base receptacle now used and adapted to receive and be connected to the standard plug associated with the electrical household articles or utensils and a prime desideratum of my present invention comprehend the provision of such a combination plug and socket.

The principal objects of my invention may therefore be said to include, besides the provision of a combination plug and socket having the function and uses above outlined, the further provision of a plug and socket in which a female unit or socket is attached to a male unit or plug to form a unitary device, the latter being constructed to be received by a standard base receptacle and the

former being adapted to receive the standard threaded plug, the units being so combined as to provide for economy in manufacture and rigidity of the parts, the plug and socket forming an inexpensive, low cost 60 of production, electrical fixture.

To the accomplishment of the foregoing and such other objects as may hereinafter appear, my invention consists in the elements and their relation one to the other, 65 as hereinafter particularly described and sought to be defined in the claims, reference being had to the accompanying drawings which show a preferred embodiment of my invention and in which:

Figure 1 is an elevational view in cross section of my combination plug and socket showing the manner of its use, and

Figure 2 is a bottom plan view thereof.

Referring to the drawings, the combination plug and socket comprises, generically, the male unit or plug P and the female unit or socket S, the former being adapted to be received by and fit into the standard base receptacle R, the plug P and socket S forming a unitary device.

The plug P preferably comprises a body 10 made of insulating material such as porcelain, fibre or the like, the said body portion 10 having a lower portion 11 being 85 of rectangular cross-sectional configuration to fit the standard type of base receptacle R and being provided with the flanged portion 12 intended to cover the opening of the base receptacle, the body 10 further including an upper portion 13 preferably of circular cross sectional area. Attached to the insulating body 10 and mounted in opposed relation preferably externally thereof, I provide the metallic strips 14 and 15, the latter comprising contact elements adapted to electrically connect with the opposed contact terminals (not shown) of the base receptacle R. The metallic strips 14 and 15 are preferably provided at the bottom ends thereof with the inturned flanged portions 16 and 17, the portion 11 of the insulating body 10 being suitably contoured to permit the inturning of these end portions, this for the purpose of facilitating entry of the plug into the receptacle R. The metallic strips or contact elements 14 and 15 are further provided with the preferably integral arms or branches 18 and 19 which extend into the interior of the plug P, the body 10 being 110

provided with suitably opposed slits 20 and 21 through which the branches 18 and 19 are inserted. Arranged longitudinally of the body 10 are provided the spaced channels 22 and 23 and in these channels are arranged the conductors 24 and 25 respectively, the said conductors being connected to the branches or arms 18 and 19 respectively at their bottom portions and by means 10 of the screws or similar securing means 26 and 27 respectively, the said screws attaching the conductors and arms to the insulating plate 28, the latter being preferably provided with the separating insulating block 15 29.

The socket S which is directly attached to the plug P, comprises preferably the external shell body 30 made of insulating material, the interior threaded socket member 20 or receptacle 31, part of the said receptacle preferably threadedly engaging a corresponding threaded portion of the shell 30 as at 32 and a preferably bifurcated contact element 33 arranged centrally of the threaded socket 31, the socket and contact element providing contact means for electrically engaging the corresponding portions of a standard plug. The shell body 30 is preferably provided with an annular flange 34 and the body 10 is rabbeted as at 35 to fittingly receive the flanged portion 34, the plug and socket bodies thus forming an effective unit. The socket member 31 and contact element 33 are intended for connection 35 to the contact elements of the male member by means of the conductors 24 and 25. Accordingly, the socket member 31 is provided with opposed apertured ears 36 and 37 for receiving the bolts or similar securing means 38 and 39 respectively, the latter being located in the plug body 10, the upper end of the conductor 24 being connected to the socket member 31 as by being attached to the ear 36 by the bolt 38, as will 40 be obvious from a consideration of the drawings. If desired, a semi-circular member 40 having its ends perforated may be applied to the ears 36 and 37 with the bolts entering the perforations of the said member 40. 45 The bifurcated contact element 33 is attached to the conductor 25 and may be formed integrally therewith, the said contact element preferably being arranged to extend upwardly in the socket 31, an insulating block 41 being preferably provided to this end.

The manner of making and using my novel plug and socket will, in the main, be apparent from the above detailed descrip-

tion thereof. It will be further apparent 60 that I have provided a unit especially adapted for base receptacles and intended to permit the latter to be used with the standard plugs of ordinary household articles, the latter thus being adapted to a greater usefulness; and it will be further apparent that my combination plug may be manufactured at low cost and handled with considerable facility.

While I have shown my device in the preferred form, it will be obvious that many changes and modifications may be made in the structure disclosed without departing from the spirit of the invention defined in the following claims.

I claim:

1. A device of the class described, comprising a plug and a socket both of insulating material, the plug provided with external contact elements, and the socket with 80 internal contact elements, the plug having radial openings intermediate its ends, and the contact elements branches extending through the openings, and electrical connections between the branches and the corresponding contact elements of the socket, the free ends of the plug contact elements inturned and the adjacent end of the plug reduced to receive said inturned ends.

2. A combination plug and socket especially adapted for base receptacles comprising a male unit or plug including a body portion of rectangular configuration made of insulating material having spaced channels therein arranged longitudinally thereof and provided with oppositely positioned metallic strips mounted externally thereon, the plug being constructed to be received by and fit into a standard base receptacle with the said strips adapted to connect with 100 the contact terminals of the said receptacle, a female unit or socket attached to the male unit, the said female unit comprising an insulating shell body seated on the male plug body and forming a unitary piece therewith, a threaded receptacle mounted interiorly of the said shell body and a contact element mounted centrally of the receptacle, and conductors in said spaced channels connecting the said metallic strips of the male unit to the contact element and receptacle of the female unit, the whole comprising a unitary plug and socket.

Signed at New York city, in the county of New York and State of New York, this 115 3rd day of January, A. D. 1922.

DAVID CARL
